UNITED STATES PATENT OFFICE.

EDGAR MARCELLUS COSNER, OF HALL'S PEAK, TERRITORY OF NEW MEXICO.

WIRE STRETCHER AND CONNECTOR.

SPECIFICATION forming part of Letters Patent No. 538,946, dated February 12, 1895.

Application filed April 7, 1894. Serial No. 506,663. (No model.)

To all whom it may concern:

Be it known that I, EDGAR MARCELLUS COSNER, a citizen of the United States, residing at Hall's Peak, in the county of Mora and Territory of New Mexico, have invented certain new and useful Improvements in Wire-Stretchers; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 The special object of the invention is to make a fence-wire stretcher which will also serve to connect wires as hereinafter described.

20 Figure 1 of the drawings is a side-elevation of the lever with its attachments; Fig. 2, a detail perspective view of the sliding carrier with the connector and stretcher hook, and Fig. 3, detail views of the connector and stretcher hooks. Fig. 4 is a perspective view 25 of the lever with a part of the handle broken away and with an arrow showing the direction in which the lever is pulled to stretch the wire or bring its ends together; Fig. 5, a perspective view of the connectors and wire-30 ends, and Fig. 6 a side-elevation, showing the lever used as a stretcher.

35 In the drawings, A represents the stretching lever, whose upper end is a straight handle a and the lower end a hook a' , while in the middle is the bend a^2 , where is placed the stop a^4 and near the lower end a shoulder stop a^5 .

B is the carrier consisting preferably of a metallic yoke plate whose ends are connected 40 by a rivet on which turns a friction-roll b , so that the carrier may slide between the stops a^4 a^5 with as little friction as possible. The yoke has a projecting pivot b' bent over to work in a hole c of one of the connectors C, 45 the latter being provided with a curved hook c' on one end and a slot-hook c^2 on the other.

The curved end a' of the lever A is bifurcated and provided with a cross-rivet on which is pivoted the end-curved arm D which passes through the hole c of the second connector—which is tied detachably to this arm while the other is tied to the carrier, their curved hooks and slot-hooks being arranged in opposite directions.

50 E are the stretcher hooks, arranged in opposite directions, one pivoted on the curved end of lever A while the other is preferably secured to the carrier by a link e and pivoted piece e' .

55 In order to connect the ends of two wires, I fasten the free end of each in the slotted end of one of the connectors C, then pull the lever A forward to the right. This stretches the wires and causes the hooks c' to be brought together. The hooks, being in planes 60 at right angles to each other, will readily engage, when they are detached from the carrier and lever to form the connection between the wires.

65 In order to stretch a wire, one hook E is connected with a post and the other with the end of the wire.

70 What I claim as new, and desire to protect by Letters Patent, is—

75 1. The lever A having the handle a , end slotted hook a' , curve a^2 and stops a^4 a^5 , to adapt it to be used in the manner and for the purpose described.

80 2. The lever A and connectors C in combination with a sliding carrier B, and arms D one connector being attached to the lever hook a' by arm D and the other to the carrier as and for the purpose specified.

85 In testimony whereof I affix my signature in presence of two witnesses.

EDGAR MARCELLUS COSNER.
